UNITED STATES PATENT OFFICE

JOHN R. REPLOGLE, OF DETROIT, MICHIGAN, ASSIGNOR TO COPELAND PRODUCTS, INC.,
OF MOUNT CLEMENS, MICHIGAN, A CORPORATION OF MICHIGAN

DESIGN FOR A REFRIGERATOR CABINET

Application filed June 24, 1932. Serial No. 44,184. Term of patent 7 years.

To whom it may concern:

Be it known that I, JOHN R. REPLOGLE, a citizen of the United States, residing at Detroit, in the county of Wayne and State of Michigan, have invented a new, original, and ornamental Design for Refrigerator Cabinet, of which the following is a specification, reference being had to the accompanying drawing, forming part thereof.

In the drawing the figure is a perspective view of the refrigerator cabinet, showing my new design.

I claim:

The ornamental design for a refrigerator cabinet, as shown.

JOHN R. REPLOGLE,
